UNITED STATES PATENT OFFICE.

WILLIAM T. COTTIER, OF NAPA, ASSIGNOR OF ONE-HALF TO JOSEPH F. MONTGOMERY, OF SACRAMENTO, CALIFORNIA.

VENTILATION.

SPECIFICATION forming part of Letters Patent No. 281,027, dated July 10, 1883.

Application filed December 23, 1880. (No model.)

To all whom it may concern:

Be it known that I, WILLIAM TALBOT COTTIER, a citizen of the United States, and a resident of Napa city, in the county of Napa, in

5 the State of California, have invented certain new and useful Improvements in Ventilation, of which the following specification, with its drawings, is a full, clear, and exact description.

10 This invention relates to certain improvements in the ventilation of halls, apartments, lodging-rooms, inside water-closets, and urinals in dwelling-houses and elsewhere; to the ventilation of railway-cars, and the holds and 15 other parts of ships or vessels, and to the ventilation of buildings generally—such as school-rooms, churches, opera-houses, and legislative halls, where it is necessary to keep the air constantly changing and the foul air withdrawn 20 in order to have a pure atmosphere within the building.

The object of my invention is to adapt to 25 buildings generally a pneumatic system of ventilation which acts in obedience to the laws of pneumatics, or to those natural laws that regulate the movements of gaseous bodies, including atmospheric air, without the agency of any heating apparatus, or of artificial heat as a factor; to do away with all devices that need 30 troublesome or expensive attention, thereby rendering the system perfectly automatic, and to create such constant downward and horizontal drafts through gratings in rooms or spaces between the bowl and seat in water-closets, and then such upward drafts through 35 ducts as to remove the carbureted hydrogen and the sulphurets of ammonium and hydrogen from the water-closet as readily and as thoroughly as carbonic-acid gas and other impurities are removed by this system from the 40 parlor, the audience-chamber, or the sleeping-room; further, to obtain and preserve an 45 equable temperature in a building at all seasons of the year, whether its apartments be heated by stoves, furnaces, or hot-water pipes, so that the same temperature may exist at the 50 floor-level, practically speaking, which exists in the space occupied by a standing person, or six feet above the floor; and, further, to change the temperature of a room readily without

any disagreeable drafts, and thus to equalize the heat of such room, so that its occupants may experience nearly the same degree of warmth in any and every portion of it.

55 My invention consists in the particular features of construction and the combination of parts adapted to accomplish the ends sought, as will be more particularly explained herein-after and specifically claimed.

This invention is an improvement upon a 60 patent for ventilating an outside or yard privy, issued to Elbert Eastmond and myself January 11, 1876. The ventilator to be used in connection with this ventilation will be the one patented to me July 5, 1881. The expansion-chamber or vomitorium receives the air-currents from the several air passages or ducts, and the higher temperature naturally produced of such air inside the chamber induces a steady and constant draft through such passages from 70 the rooms; and another very important office of this intermediate receiving-chamber is to overcome and correct all tendency to downward currents of cold air from the exterior by interposing its large body of warmer air 75 between the conducting passages and the ventilator, which, by its bulk and higher temperature, absorbs and warms such cold-air blasts or currents and reverses their direction, as will be more fully explained by reference to 80 the accompanying drawings, in which—

Figure 1 is a vertical cross-section of a dwelling-house; Fig. 2, the same of a school-house; Fig. 3, a longitudinal section, and Fig. 4 a cross-section, of a railway-car; Figs. 5 and 6, 85 the same of a ship, and Fig. 7 a vertical cross-section of a urinal.

I am aware that when inside water-closets are connected with sewers or cesspools by soil-pipes methods have been devised to prevent 90 the sewer-gas from rising into the room through the bowl and seat-opening, and also to produce a downward draft through said seat-opening and bowl, and thence into a single pipe or flue which extends upward, without especial 95 enlargement or interruption, to the open air above the building. In all these cases (as illustrated by an English patent to Kalb and Allsop, No. 316, January 27, 1873, and Smith's American patent No. 136,105, February 18, 100

1873, and his reissue thereof, No. 9,425, October 19, 1880,) it will be observed that the required effect is sought to be produced by making a tight joint between the receiver or bowl and the seat 5 around the seat-opening, and connecting the lower part of the receiver or bowl, or the soil-pipe below the bowl, with a vertical flue by means of a lateral passage or pipe, and which vertical flue, without interruption or change 10 of size, extends directly up above the roof of the building. I am also aware that a method has been devised to ventilate buildings or rooms by employing registers both at the top and bottom of each room, those at the bottom 15 being in the floor and having independent horizontal pipes or ducts that lead to a single vertical foul-air duct, which is inclosed by an exterior duct containing hot air from a furnace, the design of such arrangement being to induce 20 in the interior duct an upward current in the foul air from the rooms by thus heating it, and to hasten its discharge into the upper compartment of the hot-air chamber in the attic, while the hot air in the exterior duct 25 and the heated or warm air from the top of the room, after passing through registers near the ceiling into such exterior duct, are emptied into the lower compartment of such hot-air chamber, there being dampers provided or 30 placed in the partition between the two compartments, by which, under the charge of an attendant, the escape of heated air through a main ventilator on the roof may be arrested or controlled as circumstances may seem to require. This is the subject-matter of a patent 35 issued to Patrick Mihan, No. 151,997, June 16, 1874. I am further aware that air flues, ducts, or passages have been connected with rooms, either at the top or bottom, or both, 40 and that artificial draft has been produced through these ducts, flues, or passages by fan or other blast, or by connecting them with or placing them in proximity to a chimney or other means of heating and inducing a draft, 45 and I do not claim, broadly, any of these devices; but these devices, although somewhat similar in certain respects to this invention, differ very widely from it. For instance, this invention, designed to ventilate rooms, inside 50 water-closets, and various other places, has for its essential features the interposition of a tight air chamber, receiver, or vomitorium of an enlarged area, as before described, situated in the attic, between the exterior ventilator and 55 the several peculiarly-arranged air or draft passages or ducts which empty into such chamber; gratings let into the base-boards of rooms, and, in the case of inside water-closets, an open air-space between the seat and bowl, 60 all constituting arrangements not found in connection with those services. A downward draft is maintained, in consequence of such arrangement, in all the rooms, and a horizontal draft through the gratings in the base-boards by the 65 influence or agency of the upward draft in the air passages or ducts leading from them, and

a like downward draft through the opening in the water-closet seat is similarly maintained by the force of the upward draft in the air-duct leading from such closet, the influence of 70 which upward draft is extended through the open space between the bowl and seat, even up through the seat-opening into the water-closet room, as such open-air space bears the same relation to the bowl and other portions of the 75 water-closet as do the gratings in the base-boards to the apartments generally. The downward and horizontal drafts in the rooms and through the gratings in the base-boards, and also in the seat-opening and space between the 80 seat and bowl, are measurably superinduced by the ventilator above the roof by the aid it affords in drawing or sucking out the foul air or gases from the vomitoriums, whereby a partial vacuum is created in them, and by which 85 action or effect strength is added to the upward draft through the various or numerous air-ducts.

In the drawings the various parts of this invention are designated by letters as follows: 90

A represents rooms, apartments, halls, and the interior of ships or of railway-cars to be ventilated; B, air or draft passages or ducts; C, the expansion-chamber in the attic or under the deck of ship or roof of railway-car, into 95 which the air passages or ducts leading from rooms, the cabins or holds of ships, railway-cars, urinals, or inside water-closets open; D, the ventilator over the outlet from the expansion chamber or chambers; a, gratings for the 100 impure air to escape from rooms, ships, railway-cars, and other places into the air passages or ducts; b, partitions in the ducts B to keep the currents of impure air rising from a lower story from entering gratings a in an up- 105 per story, or to prevent gases from a water-closet in a lower story from entering those situated on stories above; E, water-closet room and bath-room combined, or either separately; G, water-closet seat; I, seat-opening in water- 110 closet seat; K, water-closet bowl; M, separate expansion-chamber, if desired or required, for sewer-gases or other exhalations from the water-closet, such separate expansion-chambers to be provided with a separate ventilator; N', 115 hood which overhangs or partially covers a urinal; d, air-space between the bowl and seat in an inside water-closet.

The air or draft passages or ducts B are located within the outer walls of the building, or between the partition-walls of its several apartments A. These passages or ducts B should be as numerous as may be deemed desirable or necessary, and may be arranged at will in the hollow spaces left between the outer 120 and inner walls and the studding when constructing wooden buildings. In brick buildings they may be constructed in the walls, or between the inner surface of the walls and the plastering. The gratings a, opening into the 125 several draft passages or ducts, are placed in the inner walls at the floor-level, or in the 130

base-boards only, and may be of any desired or necessary number. It has been ascertained by experiment, however, that they should rather be numerous, and not very large, than 5 few in number, and of correspondingly greater capacity, as then the movements of air in a room are likely to be more gentle and uniform, and consequently more agreeable. These gratings may be of any ornamental pattern to 10 suit different tastes. In buildings of more than one story partitions *b* should be inserted in the air passages or ducts, to extend a short distance above the floor-level in upper stories, in order that the foul air from below shall be 15 conducted upward past the gratings *a* upon the floor above, without interfering with the ventilation of the upper portion of the building. When connected with inside water-closets, or rooms *E*, in which such water-closets 20 are situated, these passages or ducts *B* should open below into or connect with the air-space *d*, between the seat *G* and the bowl *K*. To allow such space *d* to be formed or established, and thereby to effect such connection, which 25 is indispensably necessary for conveying sewer-gas and other noxious gases from the bowl into such ventilating-ducts *B*, or any impure air from the water-closet room *E* through the seat-opening *I* into similar ducts, alike designated, 30 the bowl *K* must not in any case come up to the seat *G*. By this arrangement, as before explained, there is created and insured, under all conditions of the atmosphere, aided by the 35 ventilator *D*, a constant downward draft through the seat-opening *I*, a horizontal draft through the space *d*, and an upward draft through duct *B*. The ventilator acts much like an air-pump, by creating in the air-chamber or vomitorium a partial vacuum, and in 40 the duct *B* a strong upward current, thus inducing, necessarily, a downward draft through the seat-opening and a horizontal draft through the space *d*, between the seat and bowl, thereby arresting all noxious vapors and sewer-gas, 45 which always tend to escape from the bowl through the seat-opening into the apartments of a building. By this downward and horizontal draft (effects of the strong upward draft in the ventilating-duct *B*) these poisonous 50 gases from the water-closet and sewer are deflected and drawn upward into such ventilating-duct *B*, and thence through the expansion-chamber and the ventilator into the open air. It will now be apparent that no downward and horizontal draft communicating with the duct *B* could be established if the seat and bowl were hermetically sealed to each other. 55 This invention does not interfere with or require the ordinary trapping or other means 60 yet devised to prevent sewer-gas or effluvia from cesspools from invading buildings. All foul air escaping from the rooms through the ducts is emptied into the expansion-chamber *C*, while all sewer-gas or other exhalations 65 from the water-closets conveyed through separate ducts *B* are emptied into the same chamber, *C*, or into a separate expansion-chamber in the same attic, if such separate expansion-chamber be preferred, each of such chambers being provided with a separate ventilator for 70 the discharge of its contents respectively. The higher temperature of the air or gas in these expansion-chambers, always naturally or incidentally produced—that is, without any special heating apparatus—superinduces by 75 such condition a constant upward draft from all the rooms and water-closets below under all conditions of the atmosphere. In other words, the comparatively warmer temperature and lighter specific gravity of the air or gases 80 in the chambers, constituting by such qualities a partial vacuum, cause an upward draft in the ducts *B* and induce the heavier vitiated air in the rooms to seek egress through the gratings *a*, and the sewer-gas or effluvia in the 85 water-closets through the spaces *d*, and thence up such ducts into such vacuum, in obedience to the natural tendency of any particular fluid to an equilibrium of temperature and of density, finally to escape through the ventilator, and 90 this without the use or aid of any surrounding heating-ducts or supplemental artificially-heated chamber or heating apparatus or any other form of artificial draft. Neither registers nor dampers are necessary; nor should 95 there be any openings from the top of the room; nor, further, should any expense be incurred in putting in pipes or ducts, whether of metal or other material, as the spaces formed or existing between the outer and inner walls and 100 the studding afford, as previously suggested, proper and suitable passages, it only being necessary to make them tight and continuous to create or insure a perfect draft. There must be no outlet-gratings, except those at the 105 floor-level or in the base-boards, although transoms over the doors are permitted, besides such other means or provision as may be found necessary to supply fresh air to the rooms from the outside of the building or from its 110 halls, no such provision for ingress being allowed, however, to connect or to interfere with any of the air-ducts *B*. It should be understood that the entire attic is not always used 115 as a vomitorium. The entire space under a flat low roof might be so used, as it would not be needed for other purposes; but in a modern dwelling, where it may be desirable to finish off portions of the attic for storage-rooms or sleeping-apartments, then only the remaining 120 space in the upper part of it is used for such vomitorium.

When this invention is used in railway-cars, the passages *B* are constructed between the inner and outer walls, and are made to communicate with the interior of such cars at the floor-level by means of open gratings, as in rooms, and lead to and open into a space beneath the car-roof and above the inner ceiling, which space will form or constitute the expansion-chamber *C*, the ventilator being placed over 130 an opening through the roof from the upper

part of such chamber, and when employed for the ventilation of the water-closets in railway-cars a close water-tight receptacle for the reception of the excreta must be placed beneath the seat, so that no air nor draft will come in from below, but the draft will all take place from the closet down through the seat-opening, then through an open space, *d*, between the top of the receptacle and the under 10 part of the seat, as in inside water-closets, and thence upward through separate ducts *B*, a separate expansion-chamber, *M*, and finally through a separate ventilator, *D*, as in other cases, thus keeping the air in the closet 15 perfectly pure and fresh. The excrementitious matters stored in these receptacles may by some suitable process be emptied at stated times and places, as may be most convenient or desirable, and be disposed of for fertilizing 20 purposes, instead of being discharged, as usual, at random along the track and at depots, to create nuisances at many points.

In the ventilation of ships or vessels the expansion-chamber *C* would be formed by the 25 deck and a ceiling beneath the deck, and the passages or ducts *B* would be formed by the outer sides and the inner sheathing or lining of the ship, the gratings *a* being inserted in such inner sheathing, near the bottom of the 30 hold or the floors of the cabins, so as to communicate with these passages *B* in the same manner as has been shown with regard to rooms or buildings. The ventilator *D* may pass up through a mast, or be fitted in any other 35 suitable manner above the deck. When applied to urinals, the air-passages *B* and expansion-chamber *C* are formed substantially as hereinbefore shown and described; but the opening into the air passage occurs at a suitable 40 height above the urinal, which is partly covered by a hood, *N*, designed to properly direct the current of air and the emanations from such urinal into such air-passage *B*, to be through it conveyed away into the open 45 air, as in other cases described in this specification.

In executing any work necessary for the application of this system of ventilation, it is indispensable that all floors, walls containing 50 flues or ducts, fittings, joints, or connections, should be made substantially air-tight, so that no air nor gas shall enter or escape from any flue, passage, duct, or air-chamber, whether connected with or designed to ventilate rooms, 55 halls, railway-cars, ships, urinals, or inside water-closets, except through the gratings, openings, or spaces especially arranged and intended for the admission of either pure or foul air, or of noxious gases into such flues, passages, 60 ducts, or air-chambers, or for their discharge therefrom, to be thence finally conveyed through the ventilator into the open air. A failure to observe this injunction would defeat the purpose intended and render the invention 65 inoperative.

The figures in the drawings sufficiently illustrate the application of this invention to railway-cars and ships without further description than has already been given herein. All the parts or features used when constructing this pneumatic system of ventilation for buildings are used in applying it to railway-cars and ships. The construction and application of the system, wherever used, are the same.

Having thus described my invention, what I claim as new, and desire to secure by Letters Patent, is—

1. In buildings, dwelling-houses, and other apartments, the combination, with vertical 80 draft-passages *B*, built between walls, and having partitions *b* between different floors, of gratings *a* in the base-boards, a vomitorium, *C*, in the attic, and a ventilator, *D*, above the roof, thereby creating an open communication 85 between the several apartments *A* and the external atmosphere above the building, in order to obtain automatic ventilation thereof independently of artificial heating apparatus, and at all times to obtain a downward draft of the 90 vitiated air until it has escaped through the gratings into the draft-passages, substantially as described.

2. In the ventilation of one or more water-closet rooms, *E*, within a building, the combination, with the vertical duct *B*, having partitions *b*² between different floors, of the bowl *K*, hermetically inclosed, except at the seat-opening *I*, and with an air-space, *d*, between the bowl and the seat *G*, a vomitorium in the 100 attic, and a ventilator above the roof, in order to obtain automatic ventilation of a water-closet independently of any artificial heating-apparatus, and at all times to obtain a downward draft through the seat-opening, whereby 105 to arrest the escape into the building of sewer-gas and effluvia by deflecting the same through the air-space *d* into the duct *B*², to be thence discharged through the vomitorium and ejector, substantially as described.

3. In a building, the combination, with a ventilator, vomitorium, duct *B*², and one or more water-closets, of the several passages *B* and gratings *a*, communicating with one or several apartments, thus uniting the water-closet ventilation with the ventilation of the entire building, in order to strengthen and maintain the downward draft through one or more seat-openings, *I*, and to increase the speed of the water-closet draft, substantially 120 as described.

4. In the ventilation of buildings employing an expansion-chamber, a partition, *N*, dividing said chamber into two compartments, whereby the gases escaping from the water-closet are separated from the foul air escaping from the rooms.

5. In the ventilation of buildings, the combination, with vertical draft-passages *B*, having partitions *b*, of gratings *a*, a ventilator, 130

D, and a vomitorium divided into two compartments by a partition, substantially as described.

6. In the ventilation of buildings, the several air-ducts divided between floors by suitable partitions, and having independent gratings which communicate with rooms, in combination with an expansion-chamber and a

ventilator, whereby automatic ventilation is effected.

In witness whereof I have hereunto set my hand and seal.

WILLIAM TALBOT COTTIER. [L. S.]
